[57] CLAIM

The ornamental design for a combined stopwatch and clock for stethoscope, as shown and described.

DESCRIPTION

FIG. 1 is a perspective view of a combined stopwatch and clock for stethoscope showing my new design;

FIG. 2 is a front elevational view;

FIG. 3 is a right side view, the left side view being a mirror image;

FIG. 4 is a rear elevational view;

FIG. 5 is a top plan view; and,

FIG. 6 is a bottom plan view.

The broken-line showing of a stethoscope in FIG. 1 is environmented only and forms no part of the claimed design.

FIG. 1

FIG. 5

FIG. 2

FIG. 3

FIG. 4

FIG. 6
